UNITED STATES PATENT OFFICE.

CHARLES A. DANIEL, OF PHILADELPHIA, PENNSYLVANIA.

DESIGN FOR AN AUTOMOBILE-TIRE.

46,725.

Specification for Design.

Patented Dec. 8, 1914.

Application filed October 24, 1914. Serial No. 868,532. Term of patent 14 years.

To all whom it may concern:

Be it known that I, CHARLES A. DANIEL, a citizen of the United States, residing at No. 1421 Diamond street, Philadelphia, in the county of Philadelphia and State of Pennsylvania, have invented a certain new, original, and ornamental Design for an Automobile-Tire, of which the following is a specification, reference being had to the accompanying drawing, forming part thereof.

My design is shown in the accompanying drawing in which the figure is a plan view

of the tread of an automobile tire, showing the design as impressed upon it.

The design on the tread simulates a branching vine of which the stem occupies the central part of the perimeter.

I claim:

The ornamental design for an automobile tire, as shown.

CHARLES A. DANIEL.

Witnesses:

JAMES H. BELL,
E. L. FULLERTON.
